UNITED STATES PATENT OFFICE.

RICHARD H. MATHER, OF WINDSOR, CONNECTICUT.

DESIGN FOR A HANDLE FOR BICYCLE HANDLE-BARS.

SPECIFICATION forming part of Design No. 31,257, dated July 18, 1899.

Application filed February 17, 1897. Serial No. 623,885. Term of patent 7 years.

To all whom it may concern:

Be it known that I, RICHARD H. MATHER, a citizen of the United States, residing at Windsor, in the county of Hartford and State 5 of Connecticut, have invented and produced a new and original Design for a Handle for Bicycle Handle-Bars, of which the following is a specification, reference being had to the accompanying drawing, in which the only figure of the drawing is a side elevation of a handle showing my design.

My design relates to handles for the handle-bars of bicycles and to that class of handles that are placed on the ends of the handle-bar in longitudinal alinement therewith.

B designates the body or main portion of the handle, and C the tips or caps at the respective ends of the handle. The body or main portion in general is of an ordinary form, round in end view and tapering gently each way from the middle, as seen in side

view. Its surface is ribbed with rounded beads *a*, arranged closely together and extending around the handle-body on a slight incline. The spaces between the adjoining beads *a* come to a sharp point like the bottom of a V. The caps *C* are correspondingly ribbed, as at *b*, and slightly tapering; but the beads at the outer ends do not fully partake of the rounded form of the beads at the inner ends of the caps and body of the handle, as they are beveled off on their outer face down to the smaller diameter of said caps, as shown. The caps are shaded to make them darker than the body of the handle. 35

What I claim is—

The design for a handle for bicycle handle-bars substantially as shown and described.

RICHARD H. MATHER.
